UNITED STATES PATENT OFFICE

2,206,197

WIND DRIVEN VEHICLE

Reuben Lindstrom, Wisconsin Rapids, Wis.

Application November 27, 1939, Serial No. 306,229

5 Claims. (Cl. 46—217)

My invention relates to vehicles and particularly to vehicles arranged for propulsion by power derived from wind directed thereagainst.

In wind driven vehicles it is desirable to avoid use of elevated wind responsive devices such as sails, windmills and the like and this is particularly true in toy vehicles simulating various types of full-sized vehicles for the reason that it is desired that the toy vehicle resemble as nearly as possible the full sized vehicle which it simulates.

An object of my invention is to provide a wind driven vehicle capable of efficient operation without the need for elevated wind-responsive devices thereon.

Another object is to provide such a vehicle wherein wheels provided for certain primary functions are so constructed as to also function as wind actuated impellers.

Still another object is to provide such a vehicle wherein the spokes of wheels are shaped and positioned to constitute wind responsive impeller blades.

A further object is to provide such a vehicle of simple, light and inexpensive construction.

These and other objects and advantages of the invention will more fully appear from the following description made in connection with the accompanying drawing, wherein like reference characters refer to the same parts throughout the views, and, in which:

Fig. 1 is a side view of a vehicle incorporating embodiments of my invention;

Fig. 2 is a top view; and

Fig. 3 is a partial sectional view taken on the line 3—3 of Fig. 1, as indicated by the arrows.

Referring to the drawing a toy simulating a steam traction engine is shown with an embodiment of my invention incorporated therein. The toy tractor may be constructed chiefly of sheet metal formed to simulate in miniature the various parts of a conventional type of steam traction engine. A horizontally disposed cylindrical structure 4 is formed to have the approximate appearance of the boiler and fire box of a traction engine. A tubular member 5 is mounted on the forward end of the boiler structure 4 in vertically upstanding relation therewith to have the appearance of a smoke stack. A relatively small cylindrical member 6 is placed on the upper forward portion of the boiler 4 to represent the cylinder of the steam engine, and a rod 7 representing a piston rod is placed in rearwardly projecting relation with the rear end of the engine cylinder 6 and is associated therewith for longitudinal sliding movement relative thereto. The

cross head guide 8 having a cross head 9 running therein is mounted rearwardly of the steam cylinder and the rear end of the piston rod 7 is connected to the cross head 9. Toward the rear end of the boiler structure 4 a horizontally positioned shaft 10 is disposed transversely of and above the boiler 4 and is journalled in suitably apertured bearing brackets 11 mounted on the upper side of the boiler 4. A crank wheel 12 carrying an eccentrically located crank pin 13 is mounted on the right-hand end of the shaft 10 and a connecting rod 14 is connected at its respective ends to the crank pin 13 and the cross head 9.

The lower rear portion of the boiler and fire box structure 4 carries an angularly bent plate 15 arranged as shown in Figs. 1 and 2 to form a rearwardly projecting platform. A rod 16 constituting a rear axle for the vehicle is suitably carried by the angularly bent plate 15 so as to extend transversely of the vehicle and project outwardly of the boiler and fire box structure 4 at each side of the vehicle. A pinion 17 is mounted on the left-hand portion of the shaft 10 in longitudinally slidable but nonrotatable relation therewith. A grooved shifting collar 18 is carried by the pinion 17 in coaxial relation therewith and in movable relation with the shaft 10. A helical compression spring 19 is placed on the shaft 10 between the shifting collar 18 and the nearest one of the bearing brackets 11 so as to bear at its respective ends against the shifting collar 18 and the bearing bracket 11. A double armed shifting lever 20 is pivotally mounted on a vertical pin 21 carried by a bracket 22 secured to the top of the boiler and fire box structure 4 a moderate distance rearwardly of the shaft 10. The rear end of the shifting lever 20 is formed into a handle 20a and the forward end of the shifting lever 20 is provided with a shifting pin 23 projecting into the groove of the grooved shifting collar 18. Obviously the pinion 17 may be shifted longitudinally of the shaft 10 by manipulation of the handle 20a. A gear 24 is mounted on a pin 25 carried by the left-hand side of the boiler and fire box structure 4. The gear 24 is so positioned as to normally be meshed with the pinion 17 when the pinion 17 is in its outwardly shifted position. The pinion 17 when shifted inwardly against the pressure of the spring 19 will be removed from meshing relation with the gear 24.

A large gear 26 is meshed with the gear 24 and is rotatably mounted on the left-hand portion of the rear axle 16 and is adapted for attachment to a drive wheel to be described.

50

55

Drive wheels 27 are rotatably mounted on respective ends of the rear axle 16 as shown in Figs. 1 and 2. Each of the drive wheels includes a rim 27a disposed concentrically of the rear axle 16 and also includes a hub 27b by means of which the wheels 27 are rotatably mounted on the axle 16. Extending radially from the hub 27b to the rim 27a of each of the drive wheels 27 is a series of spokes 28. The spokes 28 are of relatively flat, wide and thin proportions and, as indicated in Figs. 1 and 3, are each disposed at an angle to the plane of the wheel 27 with which they are associated. The group of spokes 28 on each of the drive wheels 27 will function as a wind actuated impeller so that wind directed against the drive wheels 27 will result in a torque being applied to the drive wheels 27.

A flywheel 29 is mounted on the left-hand end of the shaft 10 and includes a rim 29a and a hub 29b. Radially extending spokes 30 are provided for connecting the hub 29b and the rim 29a. The spokes 30 are constructed and arranged in the same manner as the spokes 28 of the drive wheels 27 so as to enable the flywheel 29 to function also as a wind actuated impeller for applying torque to the shaft 10, whereby such torque will be transmitted through the pinion 17, the gear 24 and the gear 26 to the left-hand drive wheel 27. The gear 26 is, of course, connected with the left-hand drive wheel 27 in non-rotatable relation therewith.

A downwardly projecting bracket 31 is provided on the lower side of the forward end of the boiler 4 and a front axle 32 is pivotally attached in its medial portion to the bottom end of the bracket 31 for rotative movement of the front axle 32 in a horizontal plane. Front wheels 33 are rotatably mounted on each end of the front axle 32. Each front wheel 33 includes a rim 33a and a hub 33b. A series of spokes 34 extend radially from the hub 33b to the rim 33a of each of the front wheels 33. The spokes 34 are constructed and arranged in the same general manner as the spokes 28 of the drive wheels 27 so that the front wheels 33 constitute wind actuated impellers for operation to assist in moving the tractor over the ground.

Steering means for the front wheels is provided. Included in the steering means is a steering wheel 35 mounted on the rear end of a downwardly and forwardly inclined steering shaft 36. The upper end of the steering shaft 36 is journaled in a bearing element 37 suitably attached to the boiler and fire box structure 4. A downwardly projecting bracket 37 is attached to the lower side of the medial portion of the boiler structure 4 and carries a bearing element 38 in which the lower portion of the steering shaft 36 is journaled. The lower end of the steering shaft 36 is provided with a winding drum 39 around which the medial portion of a cable 40 is wound through several turns. The portions of the cable 40 extending away from the drum 39 pass over pulleys 41 mounted adjacent the respective left and right-hand ends of the bracket 37. From the pulleys 41 the end portions of the cable 40 extend forwardly at such angles as to cross one another and at their forward ends are attached to clips 42 secured on the respective right and left-hand portions of the front axle 32. It should be apparent that steering movements of the front axle 32 may be effected by rotation of the steering wheel 35. Mounted on top of the forward portion of the boiler 4 is a structure 43 simulating a flyball governor. The governor 43 includes a vertical shaft

44 journaled in a suitably apertured bracket structure 45 which is mounted on the upper side of the boiler 4. Vertically spaced annular elements 46 and 47 are mounted on the shaft 44 as shown in Fig. 1, and a series of bent elements 48 simulating the toggle assemblies which support the flyball weights of a regular flyball governor are attached at their upper and lower ends to the annular elements 46 and 47. A series of hemispherical cups 49 are mounted on the medial portions of the respective bent elements 48 to simulate the flyball weights of a flyball governor. The cups 49 all face in a common circumferential direction relative to the shaft 44 so that the cups 49 will enable the governor structure 43 to function in the manner of an anemometer type wind turbine. A pulley 50 is mounted on the lower portion of the governor shaft 44 and is connected through an endless belt 51 to a pulley 52 mounted on the engine shaft 10 whereby torque developed by the wind turbine comprised by the governor structure 43 will be transmitted to the shaft 10 and from the shaft 10 through previously described gearing to the left-hand wheel drive 27. The platform simulating plate 45 is bent at the rear portion thereof and extended downwardly to form a depending relatively rigid apron 15a presenting a rearwardly facing surface upon which wind from the rear or from angles within ninety degrees of the rear of the vehicle will impinge to assist in forward propulsion of the vehicle.

It is to be noted that the above described embodiment of my invention is so constructed as to be wind propelled and yet avoids the use of any wind actuated propelling device in the nature of a sail or a separate windmill or the like mounted on the vehicle. The elements of my device which derive power from the wind for propelling the device are so constructed as to have the appearance approximately of portions of the machine not ordinarily constituting wind actuated means in conventional apparatus. Furthermore, the wind actuated elements of my device function not only as such but also have a second function, namely the function of spokes in the wheels 27, 29 and 33 and the function of structure simulating the weights of a flyball governor. It is also to be noted that the wind actuated torque producing structures formed in the flywheel 29 and the governor device 43 may operate at a considerably higher speed than the wind actuated elements of the wheels 27 and 33 and that the gear reductions provided in the structure enable the wind actuated flywheel 29 and governor structure 43 to work particularly advantageously in starting the vehicle in motion.

It is apparent that I have invented a novel type of wind actuated propulsion apparatus for vehicles which may be of particularly simple, light and inexpensive construction. While I have illustrated and described an embodiment of my invention incorporated in a toy traction engine, it is to be understood that structure embodying my invention may be used with many other types of toy vehicles and also in full sized vehicles.

It will, of course, be understood that various changes may be made in the form, arrangement, details and proportions of the various parts without departing from the scope of my invention.

What is claimed is:

1. In a wind-propelled, wheel-equipped vehicle, a series of generally flat relatively thin and wide elements constituting spokes for a wheel of said

vehicle, the plane of each of said elements being disposed at an angle to the plane of said wheel whereby said series constitutes a propeller for deriving mechanical power from wind traveling

5 at an angle to the plane of said wheel.

2. In a wind-propelled, wheel-equipped vehicle including a ground-engaging traction wheel, a series of generally flat elements constituting spokes of said wheel, each of said elements being

10 so disposed relative to the remaining portions of said wheel that said series also constitutes an impeller for deriving rotary mechanical power from wind impinging thereupon.

3. In a wind-propelled, wheel-equipped vehicle

15 simulating a steam tractor having thereon a steam engine including a flywheel, a series of generally flat, relatively thin and wide elements constituting spokes for said flywheel, the plane

20 of each of said elements being disposed at an angle to the plane of said flywheel whereby said series constitutes a propeller for deriving power from the wind.

4. In a wind-propelled, wheel-equipped vehicle

including a ground-engaging wheel and a wheel elevated above the ground and connected to the ground engaging wheel through speed reduction drive mechanism, a series of flat elements constituting spokes for said ground-engaging wheel

5

and a second series of flat elements constituting spokes for said elevated wheel, said spoke elements being disposed at such angles to the planes of the corresponding wheels as to form, in conjunction with remaining portions of the respective

10

wheels, impellers for deriving rotary mechanical power from wind impinging thereupon.

5. In a wind-propelled, wheel-equipped vehicle having a platform at the rear thereof, a relatively rigid apron depending from said platform in relatively rigid relation therewith and disposed substantially in a vertical plane normal to the longitudinal axis of the vehicle so as to present a rearwardly facing surface to be impinged upon

15

20 by the wind.
